UNITED STATES PATENT OFFICE

2,382,230

TAKE-UP FOR TWIST LACE MACHINES

Albert Edward Hunter, Wollaton, England, assignor to Byard Manufacturing Company, Limited, Nottingham, England

Application January 5, 1944, Serial No. 517,030
In Great Britain November 19, 1942

7 Claims. (Cl. 87—31)

This invention relates to improvements in twist lace machines and the production of fabrics and articles thereon and has for its principal object to produce shaped articles on a twist lace machine.

In particular an object of the invention is to produce bag-shaped articles, such as hair nets, slumber caps and the like.

The principal feature of the present invention consists in the provision of means on a twist lace machine for varying the speed of take-up of the fabric across the machine.

In a preferred method of carrying the invention into effect a plurality of breadths of the fabric are produced simultaneously across the machine and means are provided whereby the speed at which the fabric of each breadth is taken up is different at different locations across the breadth. Normally, on a twist lace machine, the fabric as produced passes up the front of the facing bar and then over the porcupine roller and is finally wound on to a cylindrical fabric-receiving roller which is rotated by convenient means.

According to one embodiment of the invention the usual porcupine roller is replaced by a cam shaped roller or plurality of cam shaped rollers the periphery of which is displaced from the axis by different amounts at different positions across the breadth of such cam shaped roller or each thereof. After passing over said roller or rollers the work is wound on to a single roller or two or more rollers as desired.

According to an alternative embodiment the porcupine roller and the cylindrical fabric-receiving roller are dispensed with and the fabric as made passes up the facing bar and is then received on a member mounted to rotate about its axis, the periphery of which member from the axis is different at different positions in the width of the member.

In a particular embodiment a cross section of said member taken through its axis is substantially elliptical. A plurality of such members are mounted to rotate with a driven shaft which extends at a convenient location from one end to the other of the machine and a plurality of independent lengths of fabric are produced simultaneously across the breadth of the machine and each one of such lengths, after passing over the facing bar is secured (it may in the first instance be secured by tying or any other convenient means) to one of said members so that as the said members rotate with the shaft on which they are mounted each of said lengths is wound

on to one of said members and it will be clear that the peripheral speed of the center portion of each member will be greater than the peripheral speed of the side portions; consequently each length instead of being a length of flat or plain fabric will be of trough section.

In order that the nature of the invention may be more readily understood reference will now be made to the accompanying drawings, wherein:

Figure 1 is a fragmental cross sectional elevational view of a lace machine in accordance with this invention.

Figure 2 illustrates a length of hair net fabric produced in accordance with the invention.

Figure 3 is a perspective view of a take-up member in accordance with this invention.

Figure 4 is a sectional view of a series of said members mounted upon a shaft.

Figure 5 illustrates an alternative method of taking up the fabric in which members as illustrated in Figure 3 are employed.

Figure 6 illustrates one method of commencing the take-up operation.

Figure 7 illustrates a fragmental length of hair net fabric formed at intervals with clothing or the like.

Figure 8 is an elevational view of a modified shape of take-up member for taking up breadths of fabric of the type illustrated in Figure 7.

Figure 9 is a section on the line 9—9 of Figure 8.

Referring to Fig. 1, a part of the lace machine standard is indicated at 1. The bobbins and carriages are shown at 2 slidably mounted in combs 3, mounted on comb bars 4, the carriages being actuated by catch bars 5. Points 6 are mounted in point bars 7 and the work as made passes up the facing bar 8. The beforenamed constituent parts are normal to twist lace machines of the levers and go-through type and function normally to produce lace or openwork fabrics in known manner.

Numerous types of fabrics and articles may be produced in accordance with the invention but the invention is more particularly concerned with the manufacture of hair nets and this application of the invention will now be described by way of example.

Across the breadth of the machine a plurality of lengths of openwork fabric are produced and one of such lengths is illustrated in Figure 2. Adjacent lengths will not be connected by lacing threads.

In accordance with normal practice on lace

machines, after the work passes up over the facing bar 8 it then passes on to a porcupine roller on to a work-receiving roller. The rate of take-up of the work is, therefore, uniform across each breadth of fabric. Each breadth of fabric is subsequently severed, say along the lines 9 in Fig. 2, and each severed portion is made up into a hair net; the loose ends at the position of severing are knotted and a bag-like shape is imparted to the hair net by inserting an elastic thread along each edge which is conveniently inserted during the course of manufacture. Due to the present state of emergency the supply of elastic is limited and one object of the invention is to provide means whereby a bag-like shape is imparted without the use of elastic, but as viewed from another aspect the invention provides means whereby the meshes of the fabric in the centre part are bigger and more open than at each side so that the hair net will closely simulate hand-made hair nets of human hair and will have inherent properties tending to produce a bag-like shape irrespective of whether the elastic edging threads are used or not. To this end the usual porcupine roller is replaced by a series of cam-shaped discs 10, there being one disc for each breadth of fabric made. The discs are mounted on a square shaft 11 and separated from one another by spacers or washers 12. The shaft 11 is rounded at each end and rotates in suitable journals and is driven through a train of gearing indicated at 13 in Fig. 1. The drive may be effected through ratchet mechanism so that rotation is intermittent or the rotation may be continuous. The fabric, after passing up the facing bar, is secured to its associated member 10 (it may for example be tied on the member) and as the work proceeds the fabric is wound on to its associated member 10. Each member 10 is symmetrical having at least substantially frusto-conical side faces, and is of substantially elliptical configuration as shown in Fig. 4, being formed on each side with a boss indicated at 14. The distance between the two bosses of each member 10 across the periphery of the said member is substantially the same as the width of each breadth. It is obvious that the peripheral speed of the member 10 varies in accordance with the distance of the periphery from the axis of the shaft 11 and consequently the centre part of each breadth will be taken up at a faster rate than the edges of each breadth and as a result the meshes of the fabric lying in the central part of each breadth will be wider or more openwork than the meshes lying at or near each side. To accommodate for this the threads will preferably be drawn from beams to allow for a different rate of feed corresponding to the different rate of take-up. From the foregoing it will be obvious that after the work has been made and unwound from the members 10 it may then be severed into lengths 9—9, Fig. 2, the severed ends knotted and individual hair nets each having a bag-like shape closely simulating in appearance the hand made hair nets of human hair will thus be produced.

As the work proceeds and is wound on to the members 10 the effective diameter or overall dimensions of such member will increase consequent upon the thickness of material wound on and the peripheral speed of take up will also increase. To counteract this the train of gearing is preferably provided so that the speed of rotation of the members 10 is reduced as the work is wound on to such members. Any known or

convenient means for varying the speed of rotation automatically may be employed or, in the alternative, at different phases in the process of manufacture the machine may be temporarily stopped and a new set of gear wheels fitted. In lieu of winding the work on to the members 10 the work may pass over one of such members then under a guiding rod or roller 15 and finally is wound on to the take-up roller 16. This alternative is illustrated in Fig. 5. To avoid the necessity of knotting the severed ends of each hair net the hair nets may, if desired, be formed with what is known in the trade as terminal ends. This construction is illustrated in Fig. 7.

At spaced locations in the length of each breadth a short length of clothing 17 is produced and after each length has been manufactured the lengths are severed along the line 18 midway of each length of clothing. The clothing at the end of each hair net replaces the knots and along each edge of each breadth there may be a substantially thick thread, indicated at 19, which is securely locked in the clothing. Even if the lengths are made as shown in Fig. 2 without clothing there may, of course, be a thick thread along each edge if desired and such thread will be tied in with the knotting.

The manufacture of hair nets with terminal ends in accordance with this invention raises certain difficulties, however, because if a take-up member of the type illustrated in Fig. 3 is employed it is found that the fabric ruptures where the clothing is made, due to the fact that there is no give or elasticity in the area of the clothing, and to avoid this the member 10 is replaced by a substantially kidney-shaped member 20, illustrated in Figs. 8 and 9, the arrangement and disposition of the parts being such that the areas of clothing 18 are accommodated on the lower part of the cam and do not spread over or spread over only to a very small extent around the sides of the cam, the bulk of the fabric between the clothing areas being accommodated on the high part of the cam as clearly shown in Fig. 8. Means for varying the rate of take-up of the members 20 to accommodate for variation in effective peripheral speed consequent upon the fabric being wound on to the members 20 is preferably provided as previously described.

When commencing to manufacture openwork fabric in accordance with this invention the first ends of yarn are taken up over the facing bar and one half tied round each boss 14 of each member 10 or 20 as clearly shown in Fig. 6 and until such time as a complete length of woven fabric extends from the facing bar 2 and at least partially around each member 10 threads or wires 21 are threaded laterally through the lengths to assist in taking the strain. These may be conveniently removed sequentially as they reach the members 10 or they may, if desired, be left in position and removed when the fabric is finally withdrawn from such members; in the alternative they may be severed between adjacent breadths as they rise over the members 10 or 20.

Although the invention has been described with reference to the manufacture of hair nets it will be appreciated that it may with advantage be applied to the production of other shaped articles on twist lace machines.

I claim:

1. In a twist lace machine, a substantially disk-shaped fabric take-up member having slightly frusto-conical side faces being displaced from the axis of rotation of said take-up member by differ-

ent amounts at different positions across the breadth of said member and a rim the various portions of which are at different distances from the axis about which said member rotates.

2. In a twist lace machine, a fabric take-up member having substantially the shape of an elliptical disk with slightly frusto-conical side faces being displaced from the axis of rotation of said take-up member by different amounts at different positions across the breadth of said member, said disk being eccentrically supported rotatably about an axis normal to said side faces.

3. In a twist lace machine, a substantially disk-shaped asymmetric rotatable fabric take-up member having at least substantially frusto-conical side faces being displaced from the axis of rotation of said take-up member by different amounts at different positions across the breadth of said member and being rotatably supported about an eccentric axis extending normal to the direction of movement of the twist lace on said machine.

4. In a twist lace machine, a substantially kidney-shaped rotatable fabric take-up member having a rim the various portions of which are at different distances from the axis about which said member rotates.

5. In a twist lace machine, a substantially kidney-shaped rotatable fabric take-up member having a rim the various portions of which are at different distances from the axis about which said member rotates and having slightly frusto-conical side faces the various portions of which are at different distances from said axis of rotation at different positions across the breadth of said member.

10 6. In a twist lace machine, a substantially disk-shaped rotatable fabric take-up member having a rim the various portions of which are at different distances from the axis about which said member rotates, the periphery of said take-up member being displaced from said axis of rotation by different amounts at different positions across the breadth of said member.

15 7. In a twist lace machine, a substantially kidney-shaped rotatable fabric take-up member having a rim the various portions of which are at different distances from the axis about which said member rotates, the periphery of said take-up member being displaced from said axis of rotation by different amounts at different positions across the breadth of said member.

20 25 ALBERT EDWARD HUNTER.
